ATTYS.

UNITED STATES PATENT OFFICE.

LOUIS T. FREDERICK, OF VALPARAISO, INDIANA, ASSIGNOR, BY MESNE ASSIGNMENTS, TO CHICAGO MICA COMPANY, OF VALPARAISO, INDIANA, A CORPORATION OF INDIANA.

MICA-SEPARATING MACHINE.

Application filed December 29, 1926. Serial No. 157,805.

My invention relates to mica treating machines and is intended primarily for dividing and separating the laminae of mica plates or blocks. Mica flakes or laminae are used extensively, among other things, for making mica plate, an article having a high dielectric coefficient and consisting of flakes arranged in overlapping relation and cemented together by shellac or other binder. The quality of the flakes depends upon their size and thinness, it being desirable, for example, to produce flakes which may measure in the neighborhood of an inch and a half across and of a thickness of a few thousandths of an inch, sometimes as low as three-thousandths. The general object of my present invention is to provide mechanism for taking mica blocks or plates of considerable size and thickness and producing from them mica flakes of the character just mentioned. My present invention also resides partly in the method by which this object is carried out.

As contributing to the general object of the invention, it is my purpose to provide advantageous means for expanding the mica blocks, and in the mechanism illustrated this is accomplished by means for automatically arranging the blocks in a single layer upon a traveling conveyer, which passes through a heater and causes the blocks to be heated from all surfaces simultaneously. Another object is to provide means for further loosening the blocks by causing them to fall through a duct provided with beaters which loosen the laminae and promote the act of separation. Another ancillary object is to provide pneumatic means, including traveling members, for pulling the blocks apart. A further ancillary object is to provide means for dividing into a plurality of streams the particles leaving the pneumatic pulling mechanism. A still further object is to provide means for further subdividing the particles in the streams thus produced.

Attention is called to my copending application Serial No. 139,288 filed October 4, 1926 in which the machine and method having characteristics somewhat analogous are shown.

I accomplish my object by the mechanism and in the manner illustrated in the accompanying drawing in which

Figure 1 is a general assembly view chiefly

in sectional elevation showing the apparatus as a whole.

55

Figure 2 is a sectional view on the line 2—2 Figure 1.

Figure 3 is a sectional view on the line 3—3 Figure 1.

Figure 4 is a fragmentary sectional view 60 through the non-rotating drum taken transversely through their axes.

Like numerals denote like parts throughout the several views.

In the form selected to illustrate the invention the mica blocks are first introduced into a receptacle formed chiefly by a platform 10 and an approximately vertical wall 12. The mica blocks may or may not be previously soaked in steam, water or other fluid. They are to be subsequently heated as will be presently described, and in certain cases the heat may expand the blocks better if they have been previously soaked, although an expanding effect will be produced even though they have not been previously soaked, probably due to the fact that traces of air or moisture are usually occluded within the body of the blocks.

65

Forming one side of the receptacle, for receiving the mica blocks, is a non-rotating drum 14 having a duct 16 through which air is constantly being withdrawn. The side 18 of this drum nearest the wall 12 is foraminated or otherwise made pervious to air with the result that there is a constant inward suction of air through the side of the drum and out through one end of it. A pervious conveyer belt 20 made of wire screen or other suitable fabric passes around the drum 14 and also around a guide and traction roller 22, which is power-driven in any suitable way to cause the belt to travel. One or more guide rollers 24 may be provided for guiding the belt in its movement. The direction of travel is from the upper part of drum 14 to the upper part of pulley 22. The air passing in through the side of the drum 14 induces a suction through the screen belt 20, and this causes blocks of mica to be picked up out of the receptacle 10, 12 and caused to adhere to belt 20.

70

The result is that the blocks will adhere to the screen belt practically in a single layer. A heater is located between the drum 14 and pulley 22 for heating and expanding the mica blocks. In the form shown it consists

- of burner pipes 26 enclosed in a shallow pan or casing 28 located just beneath the upper run of the screen belt 20, and a hood 30 overlying the screen belt to conserve the heat, the gases finally passing out through a flue 32.
- 5 As previously intimated the blocks in passing through the heater or oven are expanded and the laminae loosened, rendering them much more susceptible to their subsequent treatment of agitation and separation.
- 10 A chute 34 is located in position to receive the blocks falling from the screen belt 20. Within this chute at a lower point are revolving beater arms 36 driven by a belt 38.
- 15 At the bottom of the chute 34 are two screen belts 40, 42, which are pervious to air and pass around two non-rotating drums 44, 46. These are arranged parallel and adjacent to each other, although not in actual contact.
- 20 The portions facing each other, that is, the contiguous portions, are located approximately in line with the middle chute below the lower end thereof and are foraminous. Air is constantly exhausted from them
- 25 through a duct 48 leading to the inlet of an exhaust fan 50 driven by a motor M or other suitable source of power.
- The screen belts 40, 42 are endless and at their lower end pass around sprockets 52, 54
- 30 cross connected by means of sheaves 56 and a belt 58. The belts 40, 42 have sprocket chains 60 fastened to their edges for strengthening and driving them as shown in detail in Figure 2. To promote smooth operation sprocket
- 35 wheels 62 are provided, arranged concentrically with the drums 44, 46, as illustrated in detail in Figure 3. These sprocket wheels are provided with ball bearings 64 on the hubs 66 of the drums. Driving power may be furnished in any suitable manner. In the
- 40 present instance the sprocket 52 is driven by a belt 70 from a sheave 72 which may be motor driven and operates in synchronism with a sheave 74 which drives the belt 38 previously mentioned.
- 45 When the mica flakes in chute 34 drop into the throat formed by the proximate portions of the screen belts 40, 42 the tendency is for them to be pulled apart by air suction, the
- 50 laminae following the respective belts for a portion of their travel. These belts diverge as indicated in Figures 1 and 4, with the result that the blocks are actually pulled apart as illustrated in Figure 4. The different parts
- 55 of the block are released from the screen belts as soon as the air suction is cut off by the imperforate portion of the drums 46. In dropping, the blocks are divided into two streams by inclined divider boards 76, 78 which apex
- 60 at a point somewhat beneath the throat formed by the two drums.
- Beneath the divider boards the pneumatic separating mechanism is duplicated so that the flakes of each stream shall be further subdivided. This is accomplished by screen belts
- 80, 82, 84, 86 which pass over and around drums 88, 90, 92 and 94 respectively. The driving and guiding mechanism for these supplemental screen belts is the same as above described, and by preference they are
- 70 driven from a belt 96 driven from a sheave, not shown, which is a companion to the sheave 72. Thus the beaters 36 and all the screen belts beneath them are coordinated.
- The screen belts are enclosed within a housing 98 which is open at the bottom for delivering the separated mica flakes into a receptacle 100.
- To summarize the operation, the base 10, wall 12 and adjacent side of the foraminated curved plate or drum section 18 virtually form a hopper into which the soaked or unsoaked mica blocks may be introduced. Suction draws the adjacent blocks into contact with the approximately vertical portion of the screen conveyor belt 20. The blocks then ride up onto the upper horizontal portion of the moving belt where they will thereafter stay by gravity. The blocks will automatically arrange themselves practically in a single layer for the reason that after one block has been sucked into contact with the belt it will cut off the air within its borders and while there may be some overlapping of blocks it will not be excessive. As a result, as
- 85 the blocks pass into the heater they will be subjected to heat on all sides, which will cause the blocks to expand and the laminae to be loosened. The movement of belt 20 finally brings the loosened blocks to the tower 34 where they will be subjected to the action of the beater arms 36. This mechanically loosens the laminae still further and in many cases will actually split the blocks into thinner blocks. After passing the beater arms the blocks drop into the throat formed by the proximate portions of the screen belts 40, 42 and are pneumatically pulled apart by them. Soon thereafter the split blocks leave the screen belts and are diverted laterally into two separate streams by the divider boards 76, 78 after which the flakes are again subdivided by similar mechanism.
- 100 As a result of the operation of my mechanism and method the blocks will be thoroughly loosened and the flakes separated from each other. If the desired thinness of mica flakes has not been attained by passing the block through the apparatus the first time the material may, of course, be passed through one or more times again. The action, however, is quite thorough owing, among other things, to the different characters of action to which the mica blocks are subjected and to the fact that the blocks are pneumatically divided and then subdivided without leaving the machine. It will be evident, however, that some of the elements, for example, the second set of pneumatic subdividers may be omitted without rendering the apparatus inoperative.

- 120
- 125
- 130

Having thus described my invention, what I claim as new and desire to secure by Letters Patent is:

1. In a mica treating machine, a foraminous traveling belt, means for causing a block of mica to adhere to it, and means for exerting an outward pull on the outward lamination of the block. 65
2. In a mica treating machine, a foraminous conveyor, means for causing a block of mica to adhere to said conveyor, means for separating a portion from said block, and means for similarly treating said portion. 70
3. In a mica treating machine, two endless belts pervious to air, said belts being substantially tangential at one part of the travel, and means for drawing air inward through said belts at their point of tangency for pulling apart mica blocks entering between them. 75
4. In a mica treating machine, a non-rotating drum having a portion which is pervious to air, means for drawing air in through the pervious portion of the drum, means for causing mica to be temporarily held adjacent to the pervious portion of the drum, and means for simultaneously exerting suction against the outer surface of the mica for separating the outer portion from the inner portion. 80
5. In a mica treating machine a non-rotating drum having a portion which is pervious to air, means for drawing air in through the pervious portion of the drum, a pervious traveling belt passing over the pervious portion of the drum, means for conveying mica to the belt to cause it to adhere thereto while passing over the pervious portion of the drum, a second belt pervious to air passing adjacent to the first belt at the point where the latter passes over the previous portion of the drum, the second belt traveling thence in a direction away from the first belt, and means for creating a tendency for the mica to adhere to the second belt at the above described point where it passes adjacent to the first belt. 85
6. In a mica treating machine a pair of air pervious conveyors whose paths are approximately tangential at one point and thence diverge, means for creating a tendency for a mica block to adhere to both of said conveyors at their point of tangency to split the block, and means for causing the several portions of the mica to thereafter travel separate paths. 90
7. In a mica treating machine, two endless belts pervious to air, said belts being approximately tangent at one point, and thence diverging, means for drawing air through said belts in opposite directions at the point of approximate tangency and for a slight distance beyond, and means for supplying mica blocks to said belts at a point where they are approaching tangency. 95
8. In a mica treating machine, two endless belts pervious to air, said belts being approximately tangential at one point, and thence diverging, means for drawing air through said belts in opposite directions at the point of approximate tangency and for a slight distance beyond, and means for preloosening blocks of mica and supplying them to said belts at the point of tangency. 100
9. In a mica treating machine, means for loosening the laminae of mica blocks, means for pulling the laminae apart and then dropping them, and means beneath the last mentioned means for dividing the dropping laminae into a plurality of different paths. 105
10. In a mica treating machine, screens traveling in the same general direction and closely together at one point and thence diverging, and means for creating vacuum on the remote surfaces of said screens at the point of approximate tangency for pulling the laminae of a mica block apart. 110
11. In a mica treating machine, screen belts traveling downward and closely together at one point and thence diverging, means for creating suction through said belts in opposite directions at said point, and a divider beneath said point having walls slanting downward and outward in different directions for dividing the dropping mica into two streams. 115
12. In a mica treating machine, pneumatic means for pulling the surface laminae of mica blocks in opposite directions and simultaneously advancing them in a generally downward direction but in diverging paths and then releasing them, and means apexing beneath said means for guiding the dropping flakes in different directions. 120
13. In a mica treating machine a pair of traveling belts pervious to air, means for guiding them along a path which first converges to bring the paths substantially tangential and then diverging, and means for supplying mica blocks to said belts at the point of approximate tangency to create suction in opposite directions on the outer surfaces of the blocks for splitting them. 125
14. In a mica treating machine a pair of traveling belts pervious to air, means for guiding them along a path which first converges to bring the paths substantially tangential and then diverging, means for supplying mica blocks to said belts at the point of approximate tangency to create suction in opposite directions on the outer surfaces of the blocks for splitting them, the belts traveling downward at the point of approximate tangency, means for causing the mica splittings to travel in divergent paths from the belt, and similar splitting means in at least one of said divergent paths. 130

In witness whereof, I have hereunto subscribed my name.

LOUIS T. FREDERICK.
